DISPENSING DEVICE

Fred J. McMackin, Herington, Kans.

Application July 23, 1935, Serial No. 32,795

2 Claims. (Cl. 221—60)

This invention relates to dispensing devices and more particularly to a device for dispensing the contents of the flexible tubes containing tooth paste, shaving cream or the like.

The main object of the invention is to provide a device for easily and efficiently removing the entire contents of a flexible container.

A still further object of the invention is to provide a key attachable to the end of the tube and adapted to coil the tube upon itself for removing the contents thereof.

A still further object of the invention is to provide means to easily remove the coiled and empty tube from the coiling device.

Other objects of the invention will appear as the disclosure progresses. The drawing is intended to merely indicate a possible embodiment of the invention. It is obvious that the actual needs of manufacture may necessitate certain mechanical changes. It is therefore not intended to limit the invention to the embodiment illustrated but rather to define such limits in the appended claims.

For a more general understanding of the invention attention is called to the drawing in which

Figure 1 is a view of the dispensing device shown attached to a flexible tube.

Figure 2 is a section on line 2—2 of Figure 1 showing a portion of the end of the tube coiled.

Figure 3 is a section on line 3—3 of Figure 1.

Figure 4 is a section on line 4—4 of Figure 1.

Referring now to the drawing in detail, numeral 1 designates the flexible tube containing tooth paste, shaving cream or the like, 2 the forked key member and 3 the resilient key retainer. The key member is made from one piece of material and comprises a pair of parallel spaced bars 4 and 5 spaced far enough apart to accommodate the end 6 of the tube and a handle member 7 for manually coiling up the tube.

The parallel bars 4 and 5 adjacent the handle member 7 are restricted as at 8 where they pass through one of the eyes 9 of the key retainer. The key retainer is semi-elliptical in shape and provided with a coil 10 in the center and another eye 11 opposite the eye 9.

The operation of the device is as follows: The eye 11 is slipped off the ends of the bars 4 and 5 as shown in dotted lines in Figure 1 and the end of the tube inserted between them. The eye is then replaced and the bars 4 and 5 revolved manually through the medium of the handle member 7 in an anti-clockwise direction until sufficient contents of the tube are expelled. After

use the tube can be closed up with the usual cap and the entire device with the tube attached hung up in the cabinet by the eye 10 to be used again when necessary. After the entire contents are expelled the device can easily be removed from the tube by removing the eye 11 from the bars and slipping off the coiled tube. The coil 10 will impart a sufficient amount of resiliency to the key retainer so that it can be used indefinitely without breaking. Also the said coil can be used as a means of support when the device is not in use by suspending the entire device on a hook through the medium of the coil. When the device is suspended the key retainer is swung out of contact with the body of the tube as shown in dotted lines in Figure 1.

It will thus be seen that I have provided a simple, efficient and useful device for expelling the entire contents of a flexible tube and which can fit all size tubes now on the market. Due to the restricted neck construction of the bars the key retainer cannot be entirely separated from the forked key member.

Having described my invention, I claim:

1. In a device of the class described, a key member comprising two parallel spaced bars to grip the end of a flexible tube and a handle member at one end of said bars all made from one piece of material, the said bars, adjacent said handle member being restricted, a resilient key retainer mounted on said key member, said key retainer comprising a semi-elliptical spring element provided with eyes at the ends, one of said eyes being mounted on the said restricted portions of the bars and the other on the free end of said bars.

2. In a device of the class described, a key member comprising two parallel spaced bars to grip the end of a flexible tube and a handle member at one end of said bars all made from one piece of material, each of said bars adjacent said handle member having an inwardly bent portion, the inner faces of said inwardly bent portion of each bar being in contact with each other, a resilient key retainer mounted on said key member, said key retainer comprising a semi-elliptical spring element provided with eyes at the ends, one of said eyes being of a larger diameter than the other eye, the smaller of said eyes being mounted at the inwardly bent portions of the said bars and the larger of said eyes being mounted at the free end thereof, and a loop in the center of said key retainer for providing resiliency to said key retainer.
